UNITED STATES PATENT OFFICE.

JACK W. JOHNSON, OF CHICAGO, ILLINOIS, ASSIGNOR TO RADIO VACUUM CLEANER COMPANY, OF ST. CHARLES, ILLINOIS, A CORPORATION OF ILLINOIS.

VACUUM CLEANER.

Application filed November 26, 1923. Serial No. 676,995.

To all whom it may concern:

Be it known that I, JACK W. JOHNSON, a citizen of the United States, residing at Chicago, in the county of Cook and State of Illinois, have invented new and useful Improvements in Vacuum Cleaners, of which the following is a specification.

My invention relates to improvements in vacuum-cleaners, which I have more especially devised for embodiment in the type of such cleaners wherein the fan is driven, to suck sweepings through the nozzle and fan-casing to discharge from the latter, by gearing to the fan-shaft the cleaner-carrying traction-wheels, which are rotated by propelling the cleaner on a floor, or a carpet or the like thereon. However, certain of my features of improvement are useful as well in vacuum-cleaners in which the fan is motor-driven, ordinarily by an electric motor.

In the accompanying drawings—

Figure 1 is a view in side elevation of my improved vacuum-cleaner;

Figure 2 is a top plan view of the same;

Figure 3 is a section on line 3—3, of Fig. 2;

Figure 4 is a section on the irregular line 4—4, Fig. 3;

Figure 5 is an enlarged section on line 5—5, Fig. 1, and

Fig. 6 is an enlarged section on line 6—6, Fig. 5, showing a clutch-detail.

An important feature of my improved cleaner is the casing, including the forwardly-extending nozzle and the rearwardly extending exhaust-outlet, all of which parts I prefer to form, except as to the cap hereinafter described, as an integral whole of light metal, preferably by casting it of aluminum. This casting forms the fan-chamber 7, of general circular shape, extending in a vertical plane; the exhaust-outlet 8 extending tangentially backward from the top of the fan-chamber, and the suction-nozzle 9 having its sides forming, at 9^a, outwardly expanded cheek-portions of the side-walls of the chamber and leading forwardly from points somewhat behind the transverse center and extending beyond the front thereof to form the concavely curved outwardly-

flaring sides of the nozzle, the top and bottom of the latter proceeding from the front of the chamber and forming with the said sides the laterally-elongated nozzle-mouth 10 having closed ends 11, the shape of the nozzle thus produced conforming, at least substantially to that of other vacuum-cleaners in general use. A partition 12, which is preferably an integral part of the cast casing, extends from top to bottom of the nozzle at its junction with the chamber 7. This partition is shown (Fig. 4) in its preferred forwardly-tapering shape, the wider, inner end forming a section of the periphery of the chamber 7, whence it tapers forwardly toward the transverse center of the nozzle-mouth, where it preferably terminates, as represented. The bottom of the fan-chamber is formed with a peripheral opening to render the interior accessible for introducing and removing the fan herein-after described and the opening conforms to and is closed by a segment-shaped cap 7^a removably fastened in place, as by screws 13 passed through ears 7^c projecting centrally from the ends and sides of the cap to engage lugs 7^b provided to receive the screws, on the outer surface of the chamber adjacent the opening. As will be seen, the cap in place to close the vertical, approximately circular fan-chamber forms a segment of its periphery. From near the rear ends of the cheeks 9^a project circular ears 14, 14 provided with openings 14^a in the lower parts of their peripheries, these ears affording housings for the purpose hereinafter rendered apparent, and having studs 14^b extending centrally from their flat bases to receive screws 15^a for securing disk-shaped covers 15 in place to close the outer open ends of the housings; and open-ended sleeves 16 project in alinement with each other from the cheeks 9^a into the fan-chamber centrally thereof.

A shaft 17 is inserted lengthwise, with the parts thereon hereinafter described, to extend centrally through the sleeves 16 and chamber 7 and eccentrically through the housings 14, in which the shaft-ends are shown (Fig. 5) to be longitudinally serrated 100

to roughen them for the purpose hereinafter explained. In the open outer ends of the sleeves 16 the shaft carries ball-bearings 18, the balls riding in circumferential grooves 18^a about the shaft. A fan 19, comprising blades radiating from a hub 20 and having webs 21 extending from the hub between the blades, preferably to the outer ends of the latter, as represented, surrounds the shaft at the hub 20, through which the shaft is thus passed in inserting it, the hub being confined against endwise movement between the inner ends of the sleeves 16. Ball-bearings 22 and 23, like the ball-bearings 18 and 15 having the balls riding in circumferential grooves about the shaft, carry thereon the fan at its hub, which is pinned to the cups of these ball-bearings, as shown in Fig. 5. A ball-clutch 24 (Fig. 6), of any suitable construction, has the balls confined between the member shown to be pinned to the fan-shaft at 25 in Fig. 5 and the cup 23, to engage the hub by rotating the shaft as indicated by the arrow in propelling the cleaner in the forward direction.

On each outer side of the fan-chamber 7 a bell-crank 26 (Fig. 1) is fulcrumed at its center, the forward arm of each bell-crank containing a slot 26^a, through which a screw 30 26^b passes to limit the movement of the bell-crank on its fulcrum; and each rear bell-crank arm carries an outwardly projecting pin 27, forming the axle of a traction-wheel 28 provided about its periphery with a tread 35 28^a, preferably of rubber, to engage through the openings 14^a in the housings 14, the roughened ends of the fan-shaft for driving the latter.

A brush 29 is shown in Figs. 3 and 4 to 40 be rotatably supported at its ends on journaling-screws 29^a in the ends 11 of the nozzle-mouth 10; and the brush carries on its ends wheels 29^b, preferably formed of soft rubber and having roughened or serrated 45 peripheries. These wheels protrude peripherally below the nozzle-mouth to contact with the surface being cleaned and thereby be rotated to rotate the brush for sweeping such surface in propelling the cleaner thereon.

For operating the cleaner it will be provided with the usual handle having a forked end to embrace the casing and be pivoted on the studs shown at 30, whereon it is confined against accidental removal because obstructed by the wheels 28; and the usual dust-bag will have one end attached to the outlet 8 and its opposite end connected with the handle. Showing of the handle and bag in their connection with the cleaner is omitted from the drawings as being superfluous, since it would present no features of novelty and the functions of these members will be readily understood without illustration because their use is general and well

known on vacuum-cleaners of the present class.

To operate my improved vacuum-cleaner, it is propelled back and forth in the usual manner. The weight of the casing on the 70 wheels 28 causes them to bear against the roughened ends of the fan-axis 17 with sufficient pressure to rotate the shaft in either direction, depending on the direction of moving the cleaner. This pressure will not 75 be diminished by decrease in the diameter of the wheel-treads 28^a, as through wear, since the weight of the casing will always be sufficient to turn the bell-cranks 26 on their fulcrums, to the limit permitted by the pins 80 26^b in the slots 26^a, for maintaining driving-contact of the traction-wheels with the shaft, which is thus driven at very high speed owing to the ratio of the gearing of, say, 14 to 1. 85

By propelling the cleaner in the forward direction, the clutch acts to clutch the shaft 17 to the hub 20 and thereby positively drive the fan at the very high speed referred to; and on working the cleaner in the backward 90 direction, the clutch is released from the fan-shaft, but the fan continues by its inertia to rotate in the same direction without diminution of the speed, until the cleaner, in its continued operation, is again propelled forwardly. The weight of the fan 95 causes it to function as a fly-wheel for effecting its continued rotation in the manner described when the clutch is released from the fan-hub; and this weight is augmented, to enhance that function, by the webs 21 between the fan-blades, which, preferably extend to the outer ends of the latter, not only, however, for that purpose, but also to divide the fan-blades lengthwise along their 100 centers and duplicate the fan for a purpose 105 hereinafter explained.

With the fan thus caused to rotate and the resultant powerful suction exerted through the nozzle with its mouth bearing against the surface over which the cleaner is being operated, dust and refuse, and the sweepings if a brush 29 be employed, are drawn through the nozzle and fan-chamber and discharged at the outlet 8. The partition 12 provided in the nozzle not only prevents the suction from being exerted most powerfully upon the central portion of the nozzle-mouth 10 and exerts it uniformly 110 throughout the entire length, but in the form thereof shown it divides the nozzle 115 into two similar, separate and nonintercommunicating passages respectively leading to the passages through the fan-chamber formed between the sides of the fan and the chamber-walls, to both of which last-named 120 passages the outlet 8 is common. By providing the fan with the webs 21, as described, renders it a duplicate fan, each section 125 exerts its suction-effect, mainly at least, 130

on the respective passage through the fan-chamber and that in the nozzle leading thereto, and thus more directly and satisfactorily.

5 I realize that considerable variation is possible in the details of construction herein shown and described, and I do not intend by illustrating or describing a single specific or preferred embodiment of my improvements to be limited thereto; it being my intention in the following claims to claim protection for all the novelty there may be in my invention as fully as the state of the art will permit.

15 I claim:

1. A vacuum cleaner comprising a casing formed centrally with a fan chamber, a horizontal axle traversing said casing, an elongated nozzle extending transversely of said casing adjacent said chamber, the upper and lower walls of said nozzle merging into the walls of said chamber, a partition extending from the forward wall of said chamber, between said upper and lower walls to a point adjacent the intake of said nozzle to provide separate passages from said nozzle to the sides of said chamber, said chamber having inlet openings about said axle and a tangential outlet, the side walls of said nozzle extending rearwardly in spaced relation to the side walls of said chamber and joining the latter partially about said inlet openings, a fan in said chamber mounted on said horizontal axle and means to drive said fan.

2. A vacuum-cleaner comprising a casing, a fan-chamber therein, a horizontal rotatable shaft provided in said chamber having driving surfaces on its ends, a suction-nozzle and an outlet, a fan in the chamber having a hub loosely surrounding the shaft, a clutch for engaging the hub with the shaft, said fan having means in connection with the side walls of the chamber forming passages at opposite sides of the fan, said passages connecting said nozzle and outlet, and casing-carrying traction-wheels on the casing to engage said driving surfaces on the fan-shaft for driving it.

3. In a vacuum-cleaner, a fan-chamber having an exhaust-outlet, a horizontal axle in said chamber a fan carried by said axle to rotate in a vertical plane and having blades and means extending centrally between its blades to render it a duplicate fan, a suction-nozzle extending from said chamber and containing a partition forming separate passages in the nozzle at opposite sides of its center, and means for driving the fan.

4. A vacuum-cleaner casing of integral formation comprising a vertical, approximately circular fan-chamber arranged with its axis transverse to the direction of travel for housing a fan to rotate therein about

said axis, said casing having a tangential outlet extending rearwardly from said chamber and a forwardly extending nozzle, and a central partition in the nozzle extending toward the mouth thereof from the 70 fan-chamber periphery and dividing said nozzle into passages leading to said outlet through said chamber, said fan-chamber having an opening to facilitate insertion and removal of a fan, and a closure for said 75 opening.

5. A vacuum-cleaner comprising, in combination, a vertical, approximately circular fan-chamber having an exhaust outlet and side-cheeks extending forwardly beyond 80 said chamber and forming side-portions of a nozzle terminating in a mouth, a shaft journaled to extend horizontally through the center of said chamber and carrying a clutch-member, a fan in said chamber having a hub loosely surrounding the shaft therein and engageable by said clutch-member to drive the fan by rotating the shaft in one direction, said fan forming with the walls of said chamber passages leading to 85 said outlet, a central partition in the nozzle dividing the nozzle into side-passages respectively leading to said passages in the fan-chamber, and traction-wheels journaled on the cleaner-casing to operatively engage 90 said shaft.

6. In a vacuum-cleaner having a vertical, approximately circular fan-chamber provided with an exhaust-outlet, a forward nozzle and a concentrically located side opening and containing a fan having a hub, a shaft carrying a clutch-member and insertable through the side-opening in said chamber and through said hub to extend centrally and rotatably in said chamber 100 with said clutch-member coacting with the hub to drive the fan, means in the fan-chamber for confining the hub against lateral movement on the shaft, and means for 105 driving the shaft.

7. In a vacuum cleaner, a casing comprising a central fan chamber having inlet openings concentrically arranged in the central portions of its side walls and a tangential outlet, an elongated laterally extending suction nozzle having its upper and lower walls merging into the walls of said chamber and its side walls extending in spaced relation to the side walls of said chamber 115 and joining said walls in the rear of and above and below said inlet openings to partially enclose the same, hollow bosses projecting from said enclosing walls through said inlet openings to receive fan bearings, said casing having an opening in 120 its periphery, and a closure for the latter opening.

8. A vacuum cleaner comprising a fan casing having inlets at opposite sides thereof and having an outlet, a suction nozzle 130

integral with said casing having walls extending rearwardly of and partially enclosing said inlets and providing passages from the mouth of the nozzle to said inlets, inwardly extending bosses integral with said walls and entering said inlets, a shaft journaled in said bosses and extending out-

wardly beyond said bosses, a fan operable in said casing mounted on said shaft, rollers in driving relation to the ends of said shaft, and means exteriorly of said walls pivotally connected to the cleaner and journaling said rollers.

JACK W. JOHNSON.
